UNITED STATES PATENT OFFICE.

DAVID A. URIE, OF CHICAGO, ILLINOIS.

MACHINE FOR ATTACHING COLOR CHIPS TO CARDS.

Application filed May 29, 1925. Serial No. 33,456.

My present invention is in the nature of an improvement upon the machine shown and described in Letters Patent No. 1,586,864, granted to me June 1, 1926, which is a machine that operates to a large extent automatically for producing sample cards used in the paint selling industry to illustrate the different colors and shades of mixed paints so that the purchaser can readily select the desired color. Such sample cards usually carry quite a number of color chips or small cards colored on one side to illustrate a certain shade or color, which chips are arranged in symmetrically disposed rows on the sample card. Obviously it is desirable that the cards present a neat and attractive appearance, and as large numbers of such sample cards are distributed gratuitously by paint manufacturers, it is necessary from considerations of economy that the work be done expeditiously and inexpensively, and to do such work more efficiently is the object of my present invention. This object I accomplish as illustrated in the drawings and as hereinafter described. What I regard as new is set forth in the claims.

In the accompanying drawings, which illustrate the form in which I prefer to embody my improvements,

Fig. 1 is an end view of my improved machine showing the platen which carries the blank sample cards in the position it occupies when the cards are to be applied to or removed from it. The position of said platen at the time when chips are being applied to it is indicated in dotted lines on said figure;

Fig. 2 is an enlarged partial vertical section on line 2—2 of Fig. 1;

Fig. 3 is a partial front elevation with a part of the front portion of the stand or frame broken away, and part of one of the chip holders shown in vertical section;

Fig. 4 is a plan view with one end portion of the platen broken away;

Fig. 5 is a detail, being an enlarged perspective view showing the manner in which the glue or paste-applying pads are mounted;

Fig. 6 is a partial vertical section on line 6—6 of Fig. 1;

Fig. 7 is a partial vertical cross-section on line 7—7 of Fig. 3;

Fig. 8 is a partial sectional view, taken longitudinally of the platen, on line 8—8 of Fig. 7;

Fig. 9 is a partial sectional view on line 9—9 of Fig. 7;

Fig. 10 is a perspective view of part of the platen illustrating the card-holding and positioning devices;

Fig. 11 is a partial longitudinal section of the platen on line 11—11 of Fig. 7;

Fig. 12 is a horizontal section on line 12—12 of Fig. 1;

Fig. 13 is a view showing one of the clutches in elevation, being a section taken on line 13—13 of Fig. 12;

Fig. 14 is a section on line 14—14 of Fig. 12 showing part of the mechanism for actuating the chip-applying plungers; and

Fig. 15 is a section on line 15—15 of Fig. 12 showing the braking device.

My improved machine is similar, generally speaking, to that of my said Letters Patent, in that it comprises a suitable support in the form of a stand or table having fore and aft extending rails at its ends on which a platen-carrying frame is arranged to travel back and forth. The platen, which is adapted to hold a supply of blank cards to which the color chips are to be applied, extends approximately from end to end of the machine, and is hinged to the platen-carrying frame at its lower margin so that it may be swung up to an approximately upright, but somewhat rearwardly inclined, position for convenience of the operator in applying cards thereto or removing them therefrom. It will be understood that the operator stands in front of the machine where he has convenient access to the platen and may easily swing it up or down, and also move it fore and aft when it is swung down to its horizontal or operative position.

This is practically the only work that the operator has to perform, since, as will hereinafter appear, the mechanism for applying glue or paste to the cards, and for applying chips to the glued portions thereof, operates automatically. At the rear of the stand and extending transversely of the path traveled by the platen-supporting frame is a tank or receptacle adapted to contain a suitable adhesive in liquid form, such as liquid glue.

In this tank are mounted a number of pairs of pads or daubers, the pairs corresponding in number and position to the number and position of the chips to be attached to the card, and these pads are supported so that they may be projected upwardly in the manner hereinafter described to supply glue to

the cards. The pads are adjustably mounted so that the points at which glue is applied to the cards may be arranged as desired. At the front of the stand are a number of chip holders each having a plurality of rectangular compartments or pockets, each of which is adapted to hold a pile or stack of prepared color chips, such chip-holding pockets corresponding in number and position to the number and position of the pairs of glued points on the cards. Associated with each chip holder are a number of plungers arranged to be moved vertically to lift the stacks of chips so as to apply the uppermost chip in each pocket to the lowermost card carried by the platen, which, as will be understood, then overlies the chip holders and is in a substantially horizontal position. After the application of the chips, as above stated, the plungers recede, thereby permitting the stacks of chips to drop back, and the platen is swung up to its inoperative position shown in full lines in Fig. 1. The outermost card to which the chips have just been applied is then removed, exposing a fresh card to which chips may be applied by a repetition of the cycle of operations, which consists in first swinging the platen down to the position shown in dotted lines in Fig. 1, then shoving the platen-supporting frame and platen back to the rear of the stand so that the platen then overlies the glue-applying pads, and then drawing the platen-supporting frame forward so that the platen overlies the chip holders. Mechanism is provided that is automatically actuated by the rearward movement of the platen-supporting frame to effect the operation of the glue-applying pads. and in like manner mechanism is provided that is automatically actuated by drawing the platen-supporting frame forward to the front of the stand to effect the actuation of the chip-applying devices. In the foregoing generally described particulars, my improved machine is similar to that of my said Letters Patent, but it differs therefrom in several important respects which may more conveniently be pointed out in connection with the description of the machine as illustrated in the accompanying drawings.

Referring now to the drawings, it will be seen that the stand or supporting frame of the machine illustrated is rectangular in form and comprises four corner standards or legs 16, 17, 18, 19, best shown in Fig. 12, which at their upper ends carry a horizontally disposed rectangular frame composed of end rails 20, 21 and front and rear rails 22, 23. The corners of this horizontal frame are braced by means of angle corner plates 24, 25 at the front and rear ends respectively of the side rails 20, 21, which corner plates are provided with upwardly extending lips 26, 27, respectively, which form

stops to limit the forward and rearward movement of the platen-supporting frame, as will hereinafter appear. Extending fore and aft over the side rails 20, 21 are tracks 28, 29 comprising plates secured to said rails 20, 21, respectively, as shown in Figs. 4 and 6. As will be hereinafter described, the platen-supporting frame slides on the upper surfaces of these tracks.

In addition to the front and rear rails 22, 23, I provide an intermediate rail 30 parallel with the other two which is disposed about midway between them, as shown in Fig. 7, and supported by the rear rail 23 and the intermediate rail 30 is a tank 31, preferably of sheet metal, which is adapted to hold glue or some other suitable liquid adhesive. Said tank extends from end to end of the machine between the end rails 20, 21, and is preferably supported by means of flanges 32, 33 at its front and rear upper margins arranged to extend over the upper margins of the rails 23, 30, as shown in the latter figure.

Mounted within the tank 31, so as to be movable vertically therein, is a pad-supporting frame 34, see Figs. 4, 6 and 7, which is of open-work construction and is connected at its ends to the downturned ends 35, 36 of vertically reciprocable straps 37, 38, the upper ends of which are of inverted U-shape so that said straps may extend from the end portions of the frame 34 up over the end rails 20, 21 and down on the outside of said rails, as best shown in Fig. 6. The downwardly extending portions 39, 40 of said straps are guided by passing them between guides comprising plates 41 secured to the rails 20, 21, and plates 42 secured to the plates 41 in spaced relation thereto and embracing the downwardly extending portions 40 of said straps. Thus the straps are held so that they move vertically. By reference to Figs. 4 and 6, it will be seen that the tracks 28, 29 extend over the upper end portions of the straps 35, 36, and to permit upward movement of said straps from their normal position shown in Fig. 6, said tracks are provided with openings 43 large enough to permit the upper ends of the straps to be projected through them, as indicated by dotted lines in Fig. 6. It will be understood that the straps 35, 36 are reciprocated in unison to raise or lower the frame 34, and mechanism by which this is accomplished will be hereinafter described.

Resting upon and adjustably connected to the frame 34 is a supplemental frame 44 preferably secured to the frame 34 by screw clamps 45 located at the corner portions of the supplemental frame, as shown in Figs. 4 and 6, and carried by said supplemental frame are a number of fore and aft extending pad holders 46 in the form of channel plates having their side flanges bent inward-

ly to form dove tailed channels adapted to receive similarly shaped blocks 47 and hold them in position. The channel plates 46 are preferably secured in place on the supplemental frame 44 by screw clamps 48, as shown in Fig. 5. A number of the blocks 47 are placed in each channel, the length of such blocks being equal to the distance at which the glue-applying pads are to be spaced apart. Held between consecutive blocks are a number of glue-applying pads 49 in the form of comparatively thin metal plates each having a dove tailed tongue 50 at its lower margin adapted to fit between adjoining blocks and be held thereby with the pad in an upright position, as shown in Fig. 5. As best illustrated in Fig. 4, the frame 44 is designed to carry a number of the channel plates 46 arranged parallel with each other, and each of said channel plates is adapted to carry a comparatively large number of the pads 49 which, as shown, are arranged at right angles to the length of the channel plates and, as has been suggested, may be spaced at different distances apart, depending on the spacing between the streaks of glue to be applied to the color chip carrying cards. Obviously the position of the several channel plates 46 may be adjusted by shifting them along the frame 44 to vary the spacing of the rows of color chips, and the frame 44 may easily be removed if it be desired to substitute another frame for it. The use of the blocks 44 for holding the pads in position is advantageous, because the pads are more firmly held, so that they are not apt to get out of the position in which they are set.

At the front of the machine between the intermediate rail 30 and the front rail 32 are placed the chip holders, the number and position of which correspond to the number and position of the channel plates 46, each of said chip holders being provided with pockets corresponding in number and position to the several pairs of glue-applying pads 49. This is clearly illustrated in Fig. 4, in which 51 indicates the chip holders and 52 the chip-holding pockets thereof. Each of said chip holders is in the form of a rectangular block having a row of the pockets 52 formed therein and separated by vertical partitions 53. The several chip holders are mounted in a rectangular frame or till comprising front and rear members 54, 55 and end members 56, 57, all firmly secured together and preferably made of metal. Extending along the lower margins of the front and rear members 54, 55 are inwardly projecting ribs or flanges 58, 59 which form ledges on which the end portions of the chip holders rest, the lower marginal portions of said chip holders being preferably provided with grooves in which said ledges fit, as best shown in Fig. 7. The chip holders are

clamped in position between the front and rear members 54, 55 by bolts 60, 61 passing through the members 54, 55, so that the chip holders can readily be removed or replaced by loosening said bolts. They may also be adjusted lengthwise of the till along the ledges 58, 59, since, as shown in Fig. 3, the bolts 60, 61 are fitted in longitudinally extending slots 62 in the front and rear members 54, 55, so that they may be shifted endwise of the till.

The till itself is mounted at its ends between brackets 63, 64 detachably secured to the end rails 20, 21, respectively, so as to be adjustable fore and aft. As shown in Fig. 4, the end portions of said brackets bear against the inner faces of the end rails, and said brackets are secured in position by thumb screws 65, 66 which extend through slots 67 in said end rails and screw into bosses 68, 69 at the inner sides of said brackets. By screwing up the thumb screws 65, 66 their respective brackets may be tightly drawn against the inner faces of the end rails by which they are respectively supported, but when said thumb screws are loosened the slots 67 permit said brackets to be adjusted fore and aft. For making the latter adjustment, adjusting screws 70, 71 are provided which are mounted in screw-threaded holes in the front portions of the corner plates 24, as shown in Fig. 4, and extend through the front rail 22 into engagement with the forward ends of the brackets 63, 64 with which they are rotatably connected. Therefore, by screwing the adjusting screws 70, 71 in or out, said brackets may be shifted correspondingly.

The till 54 is provided at its ends with vertically disposed ribs 72 which are arranged to slide in vertically disposed grooves at the inner faces of the end portions of the brackets 63, 64, as shown in Fig. 4, so that said till may be moved vertically with respect to said brackets, which serve the purpose not only of holding the till against endwise movement and adjusting it fore and aft, but also of guiding it as it is moved vertically. Said brackets are also provided with fixed stops 73 which project under the end members 56, 57 of the till and limit its downward movement, as shown in Fig. 4. The purpose of mounting the till so that it may move vertically is to provide for moving the several chip holders as a unit up and down to carry them toward or from the platen when it is in its horizontal position, and thereby reduce to the minimum the extent to which the stacks of chips must be moved in their respective pockets during the operation of applying the uppermost chips to the card, as will be more fully hereinafter explained.

The several stacks of chips are simultaneously moved upward in their several pock-

ets by means of a series of plungers 74, one for each pocket, each of which plungers is preferably provided with an upwardly extending slot 75 so that its lower end is bifurcated, as shown in Fig. 3. The slots 75 extend fore and aft and the several slots of all the plungers of the same chip holders are alined, so that by passing a rod 76 through such alined slots and connecting its ends to the chip holder, as shown in Fig. 7, said rod will serve to prevent the plungers from dropping below a predetermined point. Each plunger is provided at its lower end with a pair of coiled springs 77, the lower ends of which bear on a head 78 in the form of a horizontal table which extends under all the plungers of the several chip holders carried by the till, as best shown in Fig. 3. Said head is provided with a centrally located, downwardly extending stem 79, and is guided by means of guide rods 80, 81 projecting downwardly from the end portions of said head into suitable sockets 82 in a horizontally disposed plate 83 carried by a transverse beam 84 which forms a part of the frame structure of the machine. Obviously by moving the head 78 upward, the several plungers 74 may be moved upward in their respective chip-holding pockets, thereby simultaneously lifting all the stacks of chips carried by the several chip holders. The lifting power is applied yieldingly to the several plungers through the spring 77, which compensates to some extent for the reduction in the quantity of chips and makes practicable the movement of the head 78 upward to the same extent for a considerable time. When, however, the stacks of chips have been reduced to such an extent that further upward movement of the plungers is necessary in order to properly apply them, provision is made, as will be hereinafter described, for moving the head 78 upward to a higher point without, however, varying the length of its stroke.

Considering now the mechanism by which the glue pads and chip-applying plungers are operated, it will be seen by reference to Figs. 3 and 12, particularly, that an electric motor 85 is provided, which is mounted on a platform 86 provided at the lower part of the stand, as best shown in Fig. 3. Said motor drives a sleeve 87 that is loosely mounted on a shaft 88 and extends longitudinally of the rear portion of the platform 86 and is mounted in suitable bearings carried by standards 89 secured to said platform. The sleeve 87 is driven through a train of gears comprising a pinion 90 on the armature shaft of the motor, speed reducing gears 91, 92 carried by a countershaft 93 also mounted on the platform 86 in bearings carried by standards 94, and a gear 95 mounted on and rotating with the sleeve 87 and meshing with the speed reducing gear

92. The motor 85 rotates in a clockwise direction as viewed in Fig. 1, and the sleeve 87 rotates in the same direction. The sleeve 87 is therefore constantly driven by the motor 85, but ordinarily it rotates idly on the shaft 88. To further support said sleeve it is mounted intermediately in a suitable bearing carried by a standard 96 supported on the platform 86, as shown in Fig. 12.

The shaft 88 is used to actuate the glue-applying pads, and to this end it is arranged to be driven from the motor 85 through the sleeve 87 by means of clutch mechanism comprising a clutch member 97 fast on said sleeve and provided with internal teeth 98, as best shown in Fig. 13. With said clutch member cooperates another clutch member 99 which is fast on the shaft 88 and is disposed adjacent to the clutch member 97 in position to be operatively connected therewith by means of a dog 100 pivotally connected with the clutch member 99 by means of a pivot 101. A spring 102 carried by the clutch member 99 tends to move the dog 100 into engagement with the teeth 98 so as to connect the two clutch members 97 and 99 and thereby cause the shaft 88 to rotate with the sleeve 87. Said dog, however, may be moved out of engagement with the teeth 98, against the action of the spring 102, by means of an arm 103 fixedly connected with said dog and projecting beyond the periphery of the clutch member 97. As shown in Fig. 12, said arm projects rearwardly and is provided at its upper surface with a leaf spring 104 arranged so that it normally extends at an angle to said arm, as indicated by dotted lines in Fig. 13. The purpose of this spring is to absorb the shock when the arm 103 is actuated to disconnect the clutch members 97, 99 as hereinafter described. The shaft 88 is arranged to be automatically disconnected from the sleeve 87 at the end of each complete revolution of said sleeve by means of a tripping device comprising an endwise movable rod 105 mounted to slide in a bearing 106 carried by a standard 107 mounted on the platform 86, as best shown in Fig. 12, said rod when projected being in position to intercept the arm 103 and prevent rotation thereof. Consequently when the clutch members 97, 99 are engaged and rotate, at the completion of a single revolution, the arm 103 will be moved into engagement with the rod 105 and be held against further rotation while the clutch members continue their rotation of a slight extent, thereby rocking said arm to carry the dog 100 out of engagement with the teeth 98, as illustrated in Fig. 13. When this action occurs, the spring 104 first engages the rod 105, which cushions the stoppage of said arm and avoids shock. The clutch member 99 and shaft 88 accordingly stop, while the clutch member 97, and the sleeve

130

87 by which it is carried, continue to rotate. The rod 105 is retracted to release the arm 103 and permit connection of the clutch members 97, 99 by means of the dog 100 under the action of the spring 102, by devices which will now be described.

By reference to Figs. 1 and 12 it will be seen that a bell-crank lever having a depending arm 108 and a horizontal arm 109 is 10 fulcrumed at 110 on the standard 18, and that the outer end of the rod 105 is pivotally connected at 111 with the arm 108 of said bell-crank. The horizontal arm 109 of said bell-crank is pivotally connected at 112 with 15 the lower end of a rod 113, the upper end of which is pivotally connected at 114 with the horizontal arm 115 of a trip lever, also in the form of a bell-crank, fulcrumed at 116 on the upper end portion of said standard 18. 20 The upper arm 117 of said trip lever extends up alongside the rail 21 in position to be actuated by a tripping device carried by the platen-supporting frame, as will be hereinafter described, the arrangement being 25 such that when the platen-supporting frame is moved rearwardly to its paste-applying position, the trip lever will be rocked in a counter-clockwise direction as viewed in Fig. 1, thereby moving the rod 113 upward and the rod 105 outward, or to the left as 30 viewed in Fig. 12, thereby retracting the latter rod far enough to release the arm 103, which, as has been explained, connects the shaft 88 with the sleeve 87 and causes its 35 rotation. When said shaft rotates, it operates to move the straps 39, 40 upward to lift the glue-applying pads high enough to apply paste to the lowermost card carried by the platen, which then overlies said pads, as 40 will be explained more in detail later. This movement of the straps 39, 40 is effected by the following instrumentalities: As shown in Figs. 1 and 12, the shaft 88 carries at its 45 eads crank discs 118 which are fixed thereon so as to rotate therewith. Each of said discs is provided with an outwardly extending wrist pin 119 on which is journaled a block 120. Each of said blocks is connected by parallel rods 121 with a head 122, which in turn is connected by a pivot 123 with a head 124 secured to a block 125, one of which blocks is attached to the lower end of each 50 of the straps 39, 40. Cushioning springs 126 are mounted on the rods 121 for yieldingly transmitting the upward thrust of said rods to the head 122, as shown in Fig. 1. It will be seen from the foregoing description that the rods 121 may rock laterally with 55 reference to the straps 39, 40, and that by the rotation of the shaft 88 said rods act as pitmans to reciprocate the straps 39, 40 and thereby move the glue-applying pads up and down. It follows that whenever the shaft 88 is actuated, the glue-applying pads 60 will be moved up into operative position and

then be moved down again into the glue-containing tank 31, where they will remain until the next actuation of said shaft.

The reciprocation of the chip-applying plungers 74 is effected in much the same 70 way as that of the glue-applying pads, similar clutch mechanism and tripping devices being used for that purpose. Referring again to Fig. 12, it will be seen that a shaft 127 is mounted on the platform 86 near the 75 front thereof in parallel relation to the shaft 88, the end portions of the shaft 127 being journaled in bearings carried by standards 128, 129. Loosely mounted on said shaft is a sleeve 130 similar to the sleeve 87 and 80 driven therefrom by means of a chain or link belt 131 which runs over sprocket wheels 132, 133, respectively carried by the sleeves 87 and 130. A belt tightener 134 is preferably provided, as shown in Figs. 1 85 and 12. The sleeve 130 carries a clutch member 135 fixed thereto, which is similar to the clutch member 97, and cooperating with the clutch member 135 is a clutch member 136 similar to the clutch member 109 and 90 provided with an arm 137 similar to the arm 103. A trip rod 138, similar to the trip rod 105, is provided in connection with the arm 137, and is connected with the lower arm 139 of a bell-crank having a horizontal 95 arm 140 which is fulcrumed at 141 on a standard 142 rising from the platform 86 shown in Fig. 12. The arm 140 is connected to a rod 143, the upper end of which is connected to the horizontal arm 144 of a bell-crank pivoted at 145 to the side rail 21 and having an upwardly extending arm 146 corresponding with the arm 117. The arm 146 is arranged to be rocked in a clockwise direction as viewed in Fig. 1 by forward 100 movement of the platen-supporting frame into chip-applying position, and by such rocking to retract the rod 138 and release the arm 137, thereby connecting the clutch members 135, 136 and causing the shaft 127 to 105 make one complete revolution, after which it is automatically stopped by the disengagement of said clutch members in the same way as that described in connection with the shaft 88. Both the tripping devices 110 above described are normally held by gravity in the positions shown in Fig. 1 with their respective rods 105, 138 in their projected or operative positions, the weight of the rods 113, 143 being sufficient for this purpose. From the foregoing it will be seen that when the motor 85 is in operation the sleeve 130 is constantly driven, but the shaft 127 is 115 stationary except when the clutch members 135, 136 are engaged by the actuation of the trip arm 146, and that after the shaft 127 makes a complete revolution it automatically 120 stops and remains stopped until said trip lever is again actuated.

To control the rate of rotation of the 120

shafts 88 and 127, each of said shafts is preferably provided with a braking device in the form of a brake disc 147 which is mounted on and rotates with the shaft to 5 which it is applied. Over each of said brake discs extends a strap 148, one end of which is connected with the platform 86, while the other end thereof is connected to a rod 149 which passes through said platform and at 10 the under side thereof carries a spring 150 thrusting against a nut 151 screwed on the lower end of said rod. Obviously by adjusting the nut 151, the tension of the strap 148 may be regulated to control its braking 15 effect on the disc 147.

The function of the shaft 127 is to reciprocate the chip-applying plungers 74, and also to vertically reciprocate the till 54 which carries the chip holders. To this end 20 said shaft carries cams 152, 153 at its ends, and an intermediate crank disc 154, as shown in Figs. 3 and 12. Associated with the cams 152, 153 are vertically swinging arms 155, 156, respectively, which at their rear ends are 25 connected to a shaft 157 supported at the rear of the platform 86 in parallel relation to the shafts 88 and 127. Said arms respectively carry rollers 158, 159 near their forward ends which extend over the peripheries 30 of the cams 152, 153, respectively, and bear thereon, so that by rotation of the shaft 127 said arms will be swung vertically under the action of the cams. The two cams 152, 153 are of course alike in contour and arrangement. Connected with the forward ends of said arms are upwardly extending rods 160, 161 arranged to slide in suitable 35 bearings 162, 163 carried by the plate 83, as shown in Fig. 3, the connection between 40 said rods and the arms 155, 156 being preferably an adjustable one made by providing yokes 164, 165 pivotally connected to said arms and having screw connection with the lower ends of said rods, as best shown in 45 Fig. 1. As best shown in Fig. 2, the rods 160, 161 are tubular, and at their upper ends they are connected with the end members 56, 57 of the till by means of yokes 166, 167 which embrace said end portions of the 50 till, and are yieldingly connected with the upper ends of the rods 160, 161 by means of bolts 169, the lower ends of which are secured to collars 170, 171 secured to the rods 160, 161 by set screws 172. The upper ends 55 of said bolts pass through angle plates 173, 174, and above said angle plates carry nuts 175. Between the collars 170, 171 and the lower ends of the yokes 166, 167 are springs 176, 177 which tend to thrust upward on 60 said yokes and yieldingly transmit the upward thrust of the rods 160, 161 to their respective yokes and to the end portions of the till carried by them. As shown in Fig. 2, each of said yokes carries at its lower 65 end a rod 178, which telescopes in the cor-

responding tube 160 or 161 and serves to hold said yokes in alignment with their respective rods. It will be understood that the bolts 168, 169 are arranged to slide freely through the holes in the angle plates 173, 174 through which they extend, so that they do not interfere with the yielding connection between the parts as described. The function of the bolts 168, 169 is to regulate the extent to which the yokes may move away 75 from their respective rods 160, 161 under the action of the springs 176, 177, and thereby provide for properly regulating the range of movement of the till.

From the foregoing description it will 80 be understood that when the shaft 127 rotates, by reason of the consequent rotation of the cams 152, 153, the rods 160, 161 will be moved upward, thereby yieldingly thrusting upward on the end portions of the till 85 54 so that the till will be lifted into position for the application of chips to the card, carrying with it the several chip holders, which, as will be hereinafter explained, are thus moved up into engagement with the 90 lowermost card on the platen.

Rotation of the shaft 127 also moves the head or table 78 upward to actuate the several plungers 74 to move the stacks of chips simultaneously upward in their several pockets and apply the uppermost chip of each stack to the card. This is accomplished by means best shown in Figs. 3 and 12. As therein illustrated, the shaft 157 also carries a vertically swinging arm 179, similar to the arms 155, 156, which is located approximately midway between said arms and extends forward at one side of the stem 79 of the head 78, as shown in Fig. 3. To the forward end portion of said arm is attached one end of a link belt 180 which hangs pendent therefrom and is looped around a pulley 181 pivoted at 182 upon the stem 79. The opposite end of said chain passes up alongside of said stem and over a sprocket wheel 183 mounted on a shaft 184, as best shown in 105 Figs. 3 and 7. The latter shaft extends fore and aft, its forward end being mounted in a suitable bearing in the transverse beam 84, and at its forward end said shaft carries a 110 spur gear 185 adapted to be engaged by a pawl 186 pivoted at 187 on the beam 84, as shown in Fig. 3. Said pawl serves to hold the gear 185 and shaft 184 against rotation 115 in either direction, but by disengaging it from said gear the shaft and gear may be rotated to adjust the length of the bight of the chain 180. The upper end 188 of said chain hangs loosely from the sprocket wheel 183. It will be apparent from the foregoing 120 description that by swinging the arm 179 upward the bight of the chain 180 will be moved upward, and accordingly the stem 79 and head 78 will be lifted; also that by taking up or paying out the chain 180 the 125 130

normal position of the head 78 may be adjusted vertically, since in that way the point to which the pulley 181 may descend may be varied.

5. The arm 178 is moved upward by rotation of the shaft 127 through the action of the crank disc 154, which, as best shown in Figs. 3 and 14, is provided with a crank pin 189 which projects laterally under the arm 179, 10 so that when said shaft rotates said crank pin strikes a plate 190 carried at one side of the arm 179 and lifts said arm. As shown in Fig. 14, the forward end of the plate 190 is curved upwardly to permit the arm 179 15 to descend gradually as the crank pin 189 leaves said plate.

As has been explained, the shaft 127 rotates only when the clutch members 135, 136 are engaged, and such engagement is effected 20 by the actuation of the trip lever 146 resulting from the forward movement of the platen-supporting frame; also it has been pointed out that said clutch members remain in engagement only during a single complete 25 rotation thereof. It will be understood, therefore, that when said shaft is rotated the till 54 and the chip holders carried by it are moved upward, and that the head 78, which actuates the chip-applying plungers 74, is 30 also moved upward, these upward movements occurring at the beginning of the rotation of said shaft. Toward the end of such rotation they are lowered again to their normal position. It should, however, be explained in this connection that the cams 152, 35 153 are so shaped, and the crank pin 189 so located with respect to said cams, that the chip holders move up into engagement with the overlying card carried by the platen before the plungers 74 move the stacks of chips 40 upward far enough to apply the uppermost chips to the card, and that after the chips have been applied the plungers 74 are permitted to descend before the chip holders 45 move down out of engagement with the card. The object of so timing the operation of these parts is to relieve the stacks of chips of pressure tending to thrust them upward, before the chip holders are moved away 50 from the card, and thereby avoid the danger of moving the chips up out of the holders, which would be apt to cause them to become disarranged, making it necessary to rearrange them before the next chip-applying 55 operation. Moving the chip holders up into engagement with the card is also advantageous, because the stacks of chips do not have to be moved up very far when applying them to the card, and in applying the chips the uppermost chips do not have to be moved 60 appreciably beyond the upper margins of the chip holder, which also avoids danger of disarrangement and assures the application of the chips to the card at the proper points. 65 The springs between the head 78 and the

plungers 74 compensate in some measure for the reduction in the stacks of chips incident to consumption thereof, so that it is not necessary to adjust the chain 180 except after a considerable number of chips have been applied. When the stacks of chips have been reduced to a large extent, it is necessary to adjust the chain 180 so that the head 78 will stand high enough when in its lowered position to hold the plungers 74 up near the upper ends of the chip-holding pockets, since the stroke of said plungers is always approximately the same. The springs 176, 177 between the rods 160, 161 and the till transmit the upward thrust of the cams 152, 153 80 yielding to the till, and compensate for the reduction in thickness of the pile of cards carried by the platen incident to the consumption thereof, and the bolts 168, 169 hold the till normally in proper relation to the actuating devices therefor, so that the reduction in the weight of the till incident to the consumption of the chips will not cause it to assume a higher normal position under the action of the springs 176, 177 than that for which it is set.

The cards to which the color chips are to be applied are carried by a platen 191 in the form of a board that extends from end to end of the machine and is hinged at its lower margin to a platen-supporting frame 192 which comprises guide members 193 that slide on the tracks 28, 29. The hinges connecting the platen with the platen-supporting frame are best shown at 194 in Figs. 1 and 3, and it will be seen that they are arranged so that the platen may be swung up to an approximately upright but somewhat rearwardly inclined position, as shown in Fig. 1. It is provided at its upper surface near its forward margin with a handle 195 by which it may be swung up or down, and on that face which is toward the front when the platen is swung upward it is provided with fingers 196 that extend downward, when the platen is in operative position, adjacent to the inner faces of the tracks 28, 29 to assist in holding the platen against endwise movement. It will be understood that the platen is adapted to be swung down into a horizontal position, as indicated by dotted lines in Fig. 1, so that it rests on the tracks 28, 29, and then the platen with the platen-supporting frame may be moved horizontally back or forth on said tracks. The lugs 26 at the front of the frame limit its movement in a forward direction, and position it when it is at the front of the frame, and the lugs 27 perform a similar office when it is at the rear of the frame. When in the latter position, it is necessary that the platen do not interfere with the upward movement of the straps 39, 40, and therefore it is provided with holes 197, best shown in Fig. 3, that register with said straps when the

platen is in position for the application of glue to the cards carried thereby, said holes being large enough to permit the upper ends of said straps to rise through them.

- 5 On its front face the platen 191 is provided with means for holding a bunch of the cards to which the chips are to be applied, such means comprising horizontally disposed bars 198, the outer end portions 199 of which 10 are somewhat U-shaped to adapt them to fit over upright guides 200 adjustably mounted on the platen. The bars 198 are connected with the guides 200 by screws 201 which pass through transverse slots 202 in the ends 15 199, so that the bars 198 may be adjusted with reference to the screws 201. Said screws are adapted to be screwed in any of a number of holes 203 provided in the guides 200, so that the bars 198 may be variously 20 positioned on the front face of the platen, fine adjustment being obtainable by means of the slots 202. The guides 200 are adjustably secured to the upper and lower margins of the platen, so that they may be shifted 25 endwise thereof, by providing hooks 204, 205 at the lower and upper ends thereof. The hooks 204 are integral with said guides and hook over a plate 206 at the lower margin of the platen, while the hooks 205 of said 30 guides are formed separately therefrom and are adjustably connected therewith by means of screws 207, best shown in Fig. 9. By means of said screws the length of each of the guides 200 as an entirety may be adjusted 35 to hold the guide tightly in place. As shown in Fig. 10, the hooks 205 engage a plate 208 at the upper margin of the platen. It will be understood that the bunch of cards is intended to rest on the face of the platen above 40 the bars 198 and between the guides 200, and by adjusting the bars 198 vertically and the guides 200 laterally, obviously cards of almost any size can be accommodated.

The cards are held on the platen by means 45 of fingers 209, 210, 209 indicating the intermediate fingers and 210 the end fingers. Each of the end fingers 210 is secured at its lower end to a block 211 by means of a set screw 212. Each of said blocks is journaled 50 on a sleeve 213 adjustably mounted on a rod 214 secured to the lower marginal portion of the platen by end brackets 215, as shown in Fig. 4, and each of the sleeves 213 is secured in position by a set screw 216, 55 shown in Fig. 8. Attached to and preferably formed integral with each block is a rearwardly projecting arm 217 which is adapted to engage the platen-supporting frame 192 when the platen is swung back to 60 its upright position, owing to the action of a spring 218 that tends to rock the block so as to move the finger 210 thereof into engagement with the platen. Consequently 65 when the platen is moved to its rearwardly inclined position shown in Figs. 7 and 10,

the block will be rocked, against the action of said spring, to move the finger 210 connected therewith away from the front face of the platen, as illustrated in said figures. As best shown in Fig. 10, the end fingers 70 210 are offset intermediately, as shown at 219, which offset portions are adapted to register with and fit in grooves 220 in the bars 198. The purpose of providing these grooves and of offsetting the fingers 210 is 75 to permit the upper end portions of said fingers to bear closely on the cards above the bars 198, notwithstanding the fact that said fingers extend over said bars. The intermediate fingers 209 are not offset, because, 80 as shown in Fig. 3, they do not extend over the bars 198; otherwise they are mounted in the same way as the end fingers. The purpose of mounting the fingers in the manner described is to provide for their automatic operation by the swinging upward or downward of the platen, and also to permit them to be adjusted longitudinally of the platen to correspond with the adjustment of the card-supporting devices to accommodate 85 cards of different sizes. This is particularly necessary with regard to the end fingers 210, since when the guides 200 are adjusted longitudinally of the platen, it is necessary 90 to adjust the end fingers 210 correspondingly. The intermediate fingers 209 are of course so located that they do not interfere with the application of the chips to the cards; that is to say, they align with the 95 spaces between the adjoining chip holders, as shown in Fig. 3. Any suitable means may be provided for limiting the extent to which the platen may be swung back, such, for example, as the stop shown and described in my Letters Patent hereinbefore referred to. 105

While the operation of the machine has been described to a large extent in connection with the description of the construction thereof, it may be stated briefly that a bunch 110 of cards is placed on the platen when it is in the position shown in Fig. 7, at which time the fingers 209, 210 stand out away from what is then the front face of the platen. The operator then swings the platen 115 forward and downward to the position shown in dotted lines in said figure, and under the action of the springs 218 said fingers automatically swing back into engagement with the bunch of cards to hold 120 them in place as soon as the arms 217 move away from the platen-supporting frame, and thereby permit said springs to function. The motor 85 being in operation, it will be understood that the sleeves 87 and 130 are 125 rotating idly, and that the shafts 88 and 127 will not be in operation. The operator then shoves the platen-supporting frame and platen rearwardly to carry the platen over the glue tank 31. This rearward move- 130

ment trips the trip lever 117 through the instrumentality of a depending trip arm 221 carried by the platen-supporting frame, as shown in Fig. 1, which arm is pivoted at 222 so that it may swing away from the vertical in a clockwise direction, but cannot swing in a counter-clockwise direction. As the platen-supporting frame is moved rearwardly, said arm engages the upper end of the trip lever 117 and rocks it in a counter-clockwise direction as viewed in Fig. 1. This actuates the clutch mechanism comprising the clutch members 97, 99, to connect the sleeve 87 with the shaft 88, whereupon the glue pads are raised to apply glue to the lowermost card carried by the platen. Upon the completion of this operation, the glue-applying pads are returned to the tank 31 and the shaft 88 stops. The platen is then drawn forward to the position shown in dotted lines in Fig. 1, and on this forward operation the trip lever 146 that controls the operation of the shaft 127 is actuated by means of a depending trip arm 223 pivoted at 224 to the platen-supporting frame. This arm is similar to the arm 221, but is free to swing from the vertical only in the opposite direction. By forward movement of the platen it engages the trip lever 146 and rocks it in a clockwise direction as viewed in Fig. 1, thereby actuating the clutch mechanism comprising the members 135, 136 to connect shaft 127 with sleeve 130, and thereby rotate said shaft. This actuates the chip-applying plungers 74 and also the till-lifting mechanism in the manner that has been described. Chips are accordingly applied to the glued points on the card, after which the plungers and till descend and the shaft 127 stops. The platen is then lifted and after the card to which the color chips have been applied is removed, the same cycle of operations may be repeated. The purpose of mounting the arms 221, 223 as described is so that the arm 221 will act only upon rearward movement of the platen, and the arm 223 will act only on forward movement thereof. It will be understood that after the arm 221 actuates the trip lever 117, it then lies back of said lever, and when the platen is drawn forward it trips idly over said lever. In like manner when the platen is moved rearwardly, the arm 223 trips idly over the trip lever 146, but when the platen is drawn forward it operatively engages said lever and actuates it.

The springs 176, 177 not only yieldingly transmit the thrust of the rods 160, 161 to the end portions of the till, but also they provide for the adjustment of the till with reference to said rods so that its stroke may be properly regulated. By adjusting the position of the collars 170, 171, coarse adjustment of said springs may be obtained,

and finer or micrometric adjustment may be made by means of the nuts 175, on the bolts 168, 169. It will be noted that, as shown in Figs. 3 and 7, the side margins of the chip holders are cut down somewhat, the purpose of which is to permit the chip holders to move up between the card-holding fingers 209, 210, into engagement with the cards, or with the platen if no card is in place.

So far as I am aware, no one has heretofore provided a machine of the type described in which the chip holders are movable toward and from the platen, or one in which the movement of the chip holders and the operation of the chip-applying plungers are timed relatively to each other in the manner described. My invention therefore includes these features generically, and in addition it includes various specific features of improvement, all as particularly pointed out in the claims appended hereto. Furthermore, I wish it to be understood that while I have described in detail the embodiment of my invention illustrated in the drawings, my invention contemplates such variations or modifications as would occur to those skilled in the art, and therefore the claims are to be construed accordingly.

What I claim as my invention and desire to secure by Letters Patent, is—

1. In a machine for applying color chips to cards, the combination with means for holding a card, of means for applying color chips thereto comprising a holder having a pocket for holding a stack of chips, means for moving said chip-holder toward the card, and means for moving the stack of chips relatively to the chip holder to apply the outermost chip to the card.

2. In a machine for applying color chips to cards, the combination with means for holding a card, of means for applying color chips thereto comprising a holder having a pocket for holding a stack of chips, means for moving said chip-holder toward the card, and means for moving the stack of chips relatively to the chip holder to apply the outermost chip to the card after said chip-holder has been moved into proximity to the card.

3. In a machine for applying color chips to cards, the combination with means for holding a card, of means for applying color chips thereto comprising a chip holder for holding a stack of chips, means for moving said chip-holder toward the card, and means operating to move the stack of chips relatively to the chip holder to apply the outermost chip to the card after said chip-holder has been moved into proximity to the card, and to permit the stack of chips to move away from the card while said chip-holder is still in proximity thereto.

4. In a machine for applying color chips

to cards, the combination with means for holding a card, of means for applying color chips thereto comprising means for holding a stack of chips, means for moving said chip-holding means toward the card, a plunger operable to move the stack of chips toward the card, and means for moving said plunger toward and permitting it to recede from the card while said chip-holding means 10 remains in proximity to the card.

5. In a machine of the class described, the combination with a suitable support, and means for holding a card, of a chip holder having pockets to hold a plurality of stacks 15 of chips, said chip holder being movable toward and from the card, and means for moving the several stacks of chips in the holder to simultaneously apply a plurality of chips to the card.

20. 6. In a machine of the class described, the combination with a suitable support, and means for holding a card, of a chip holder movable upwardly into engagement with the card and having a pocket to hold a stack of chips, means for reciprocating the chip holder, and means operating to move the stack of chips upward in the holder to apply the uppermost chip to the card, and to permit the stack to move downwardly in the chip 25 holder.

7. In a machine of the class described, the combination with a suitable support, and a card-carrying platen movable thereon into and out of position for the application of 30 color chips to a card carried thereby, of color-chip-applying means comprising a vertically movable holder for holding a stack of chips, means for moving said chip-holder upward into engagement with the card, and 35 means operating to move the stack of chips relatively to the chip holder to apply the outermost chip to the card, and to permit the stack of chips to move downward in advance of downward movement of the 40 holder.

45. 8. In a machine of the class described, the combination with a suitable support, of a card-carrying platen movable thereon into and out of position for the application of 50 color chips to a card carried thereby, a reciprocable chip holder movable toward and from the platen, means for reciprocating the holder, a reciprocating plunger for moving the chips in the holder to apply them 55 to the card, and means for reciprocating said plunger.

60. 9. In a machine of the class described, the combination with a suitable support, and a card-carrying platen movable thereon into and out of position for the application of 65 color chips to a card carried thereby, of color-chip-applying means comprising a chip holder movable toward and from the card, means actuated by movement of the platen 70 for moving the chip holder toward the card,

and means for moving the chips relatively to the holder to apply them to the card.

10. In a machine of the class described, the combination with a suitable support, and a card-carrying platen movable thereon into and out of position for the application of 75 color chips to a card carried thereby, of color-chip-applying means comprising a chip holder movable toward and from the card, means actuated by the movement of 80 said platen for moving the chip holder toward the card, and means actuated by movement of the platen for moving the chips relatively to the holder to apply them to the 85 card.

11. In a machine of the class described, the combination with a suitable support, and a card-carrying platen movable thereon into and out of position for the application of 90 color chips to a card carried thereby, of color-chip-applying means comprising a till, a chip holder mounted on said till and movable therewith, means for moving the till toward the platen, and means for moving the chips in the holder to apply them to the 95 card.

12. In a machine of the class described, the combination with a suitable support, and a card-carrying platen movable thereon into and out of position for the application of 100 color chips to a card carried thereby, of color-chip-applying means comprising a till, a chip holder mounted on said till and movable therewith, means actuated by movement of the platen for moving the till toward the platen, and means for moving the chips in the holder to apply them to the card.

13. In a machine of the class described, the combination with a suitable support, and a card-carrying platen movable thereon into and out of position for the application of 105 color chips to a card carried thereby, of color chip-applying means comprising a chip holder movable toward and from the card, and devices actuated by the movement of the platen to first move the chip holder toward the card and subsequently to move the chips 110 relatively to the holder to apply them to the card.

14. In a machine of the class described, the combination with a suitable support, and a card-carrying platen movable thereon into and out of position for the application of 115 color chips to a card carried thereby, of color-chip-applying means comprising a chip holder movable toward and from the card, and devices actuated by the movement of the platen to move the chip holder toward the card, then to move the chips relatively 120 to the holder to apply the uppermost chips to the card, and subsequently to move the stack of chips and the chip holder away from the card in the order named.

15. In a machine of the class described, the combination with a suitable support, and 125

- 15 a card-carrying platen movable thereon into and out of position for the application of color chips to a card carried thereby, of color-chip-applying means comprising a chip holder adapted to hold a stack of chips, a plunger for moving the stack of chips toward the card, mechanism actuated by movement of the platen for moving the chip holder toward the card, and mechanism actuated by movement of the platen for actuating said plunger to move the stack of chips relatively to the holder and toward the card.
16. In a machine of the class described, the combination with a suitable support, of a till mounted on said support to slide vertically, means carried by said till for holding a plurality of chip holders, cam actuated means connected with the end portions of the till for moving the same vertically, means for moving the chips upward in the chip holders to apply them to a card, and a platen movable into and out of position over said chip holders.
17. In a machine of the class described, the combination with a suitable support, of a till mounted on said support to slide vertically, means carried by said till for holding a plurality of chip holders, cam actuated means yieldingly connected with the end portions of the till for moving the same vertically, means for moving the chips upward in the chip holders to apply them to a card, and a platen movable into and out of position over said chip holders.
18. In a machine of the class described, the combination with a suitable support, of a till mounted on said support to slide vertically, means carried by said till for holding a plurality of chip holders, cam actuated rods adjustably connected with the end portions of the till, springs interposed between said rods and the till and arranged to transmit the upward thrust of said rods to the till, means for moving the chips upward in the chip holders to apply them to a card, and a platen movable into and out of position over said chip holders.
19. In a machine of the class described, the combination with a suitable support, of a till mounted thereon to slide vertically, a plurality of chip holders mounted in said till and movable vertically therewith, plungers operating in said chip holders to move the chips therein upward, a head disposed under said plungers, springs interposed between said head and said plungers for transmitting the upward thrust of said head to said plungers, means for moving the till vertically, and means for moving said head vertically.
20. In a machine of the class described, the combination with a suitable support, of a till mounted thereon to slide vertically, a plurality of chip holders mounted in said till and movable vertically therewith, plungers operating in said chip holders to move the chips therein upward, a head disposed under said plungers, springs interposed between said head and said plungers for transmitting the upward thrust of said head to said plungers, means for moving the till vertically, means for moving said head vertically, and means for adjusting vertically the normal position of said head.
21. In a machine of the class described, the combination with a suitable support, of a till mounted thereon to slide vertically, a plurality of chip holders mounted in said till and movable vertically therewith, plungers operating in said chip holders to move the chips therein upward, a head disposed under said plungers, springs interposed between said head and said plungers for transmitting the upward thrust of said head to said plungers, cam actuated devices connected with the end portions of the till for moving the same vertically, and means for moving said head to actuate said plungers.
22. In a machine of the class described, the combination with a suitable support, of a till mounted thereon to slide vertically, a plurality of chip holders mounted in said till and movable vertically therewith, plungers operating in said chip holders to move the chips therein upward, a head disposed under said plungers, springs interposed between said head and said plungers for transmitting the upward thrust of said head to said plungers, a normally idle rotatable shaft, cams mounted on and rotating with said shaft, means actuated by said cams for moving the till vertically, means actuated by said shaft for moving said head vertically, and means operable to intermittently rotate said shaft.
23. In a machine of the class described, the combination with a suitable support, and a card-carrying platen, of a till mounted on said support to move vertically toward and from the platen, a plurality of chip holders mounted in said till and movable vertically therewith, plungers operating in said chip holders to move the chips therein upward, a head disposed under said plungers, springs interposed between said head and said plungers for transmitting the upward thrust of said head to said plungers, a normally idle rotatable shaft, devices actuated by the rotation of said shaft and operating to lift said till and said plungers to move the chip holders into contact with a card carried by the platen and to apply the chips to the card, said devices operating also to partially lower said plungers while the chip holders remain in contact with the card, and means for intermittently rotating said shaft.
24. In a machine of the class described, the combination with a suitable support, and card-holding means, of a vertically movable

till mounted on said support, means for moving said till vertically, means for adjusting said till laterally, chip holders carried by said till, plungers operating in said chip holders, and means for actuating said plungers.

25. In a machine of the class described, the combination with a suitable support, and card-holding means, of chip holders, vertically movable plungers operating in said chip holders, a head for actuating said plungers, said head having a depending stem, a vertically swinging arm, a chain connected with said arm and having a loop connection with said stem, a normally idle rotatable shaft, a crank carried by said shaft and adapted to actuate said arm to move said stem upwardly, and means for intermittently rotating said shaft.

26. In a machine of the class described, the combination with a suitable support, and card-holding means, of chip holders, vertically movable plungers operating in said chip holders, a head for actuating said plungers, said head having a depending stem, a vertically swinging arm having an upwardly curved plate, a chain connected with said arm and having a loop connection with said stem, a normally idle rotatable shaft, a crank carried by said shaft and adapted to engage said plate to actuate said arm to move said stem upwardly, and means for intermittently rotating said shaft.

27. In a machine of the class described, the combination with a suitable support, of a platen-supporting frame mounted thereon to slide fore and aft, a platen hinged to said platen-supporting frame to swing toward and from a horizontal position, and card-holding means carried by said platen comprising vertically disposed guides engaging marginal portions of said platen and adjustable longitudinally thereof, card-supporting bars connected with said guides, and swinging fingers for holding the cards on the platen between said guides.

28. In a machine of the class described, the combination with a suitable support, of a platen-supporting frame mounted thereon to slide fore and aft, a platen hinged to said platen-supporting frame to swing toward and from a horizontal position, and card-holding means carried by said platen comprising vertically disposed guides engaging marginal portions of said platen and adjustable longitudinally thereof, card-supporting bars connected with said guides, and swinging fingers for holding the cards on the platen between said guides, said fingers being independently adjustable longitudinally of the platen.

29. In a machine of the class described, the combination with a suitable support, of a platen-supporting frame mounted thereon to slide fore and aft, a platen hinged to said

platen-supporting frame to swing toward and from a horizontal position, and card-holding means carried by said platen comprising a rod mounted adjacent to the lower margin of the platen, blocks journaled on said rod, fingers carried by said blocks and extending over the platen in position to hold the cards thereon, arms carried by said blocks and operating to rock said fingers away from the platen when the platen is turned up to its inoperative position, and springs associated with said blocks tending to move said fingers into engagement with the platen.

30. In a machine of the class described, the combination with a suitable support, of a platen-supporting frame mounted thereon to slide fore and aft, a platen hinged to said platen-supporting frame to swing toward and from a horizontal position, and card-holding means carried by said platen comprising a rod mounted adjacent to the lower margin of the platen, blocks journaled on said rod, fingers carried by said blocks and extending over the platen in position to hold the cards thereon, arms carried by said blocks and operating to rock said fingers away from the platen when the platen is turned up to its inoperative position, springs associated with said blocks tending to move said fingers into engagement with the platen, guides mounted on the platen and adjustable longitudinally thereof, and card-supporting bars connected with said guides, said bars having grooves adapted to receive certain of said fingers when the latter are moved into engagement with the platen.

31. In a machine of the class described, the combination with a suitable support, of a platen-supporting frame mounted thereon to slide fore and aft, a platen hinged to said platen-supporting frame to swing toward and from a horizontal position, and card-holding means carried by said platen comprising upright guides having hooked ends adapted to engage the upper and lower margins of the platen, the hooks at one end of said guides being adjustable to clamp said guides in place, horizontally disposed bars connected with said guides for supporting cards on the platen, and fingers mounted at the lower marginal portion of the platen and movable into and out of engagement therewith, for holding the cards in place thereon.

32. In a machine of the class described, the combination with a suitable support, of a platen-supporting frame mounted thereon to slide fore and aft, a platen hinged to said platen-supporting frame to swing toward and from a horizontal position, and card-holding means carried by said platen comprising upright guides having hooked ends adapted to engage the upper and lower margins of the platen, the hooks at one end of said guides being adjustable to clamp said

guides in place, horizontally disposed bars connected with said guides for supporting cards on the platen, and fingers mounted at the lower marginal portion of the platen 5 and movable into and out of engagement therewith, for holding the cards in place thereon, said fingers being independently adjustable longitudinally of the platen.

33. In a machine of the class described, 10 the combination with a suitable supporting frame, a glue-holding tank at one side of said frame, and chip holders at the other side of said frame, of a platen-carrying frame movable over said supporting frame 15 to carry the platen into position either over said tank or over said chip holders, means operating in said tank for applying glue to the cards carried by said platen, means for moving the chips in said holders into engagement with the cards carried by said platen, and driving mechanism for actuating said devices comprising normally idle parallel shafts, a motor, means actuated by movement of said platen-carrying frame in 20 one direction for driving one of said shafts from said motor, means actuated by movement of said platen-carrying frame in the opposite direction for actuating the other shaft, and means for disconnecting said 25 shafts from said driving mechanism at the end of each complete rotation thereof.

34. In a machine of the class described, 30 the combination with a suitable supporting frame, a glue-holding tank at one side of said frame, and chip holders at the other side of said frame, of a platen-carrying frame movable over said supporting frame to carry the platen into position either over 35 said tank or over said chip holders, means operating in said tank for applying glue to the cards carried by said platen, means for moving the chips in said holders into engagement with the cards carried by said platen, and driving mechanism for actuating 40 said devices comprising normally idle parallel shafts, a motor, sleeves loosely mounted on said shafts respectively and constantly driven by said motor, clutch mechanism operable to connect said shafts respectively with the sleeves mounted thereon, means actuated by movement of said platen-carrying frame in one direction to actuate 45 the clutch mechanism associated with one of said shafts, means actuated by movement 50 of said platen-carrying frame in the opposite direction to actuate the clutch mechanism associated with the other shaft, and means for automatically disconnecting said clutch mechanisms at the end of each 55 complete revolution thereof.

35. In a machine of the class described, 60 the combination with a suitable support, of

a till mounted on said support to slide vertically, means carried by said till for holding a plurality of chip holders, cam actuated rods adjustably connected with the end portions of the till, springs interposed between said rods and the till and arranged to transmit the upward thrust of said rods to the till, means for adjusting said springs, 65 means for moving the chips upward in the chip holders to apply them to a card, and a platen movable into and out of position over said chip holders.

36. In a machine of the class described, 70 the combination with a suitable support, of a till mounted on said support to slide vertically, means carried by said till for holding a plurality of chip holders, cam actuated rods adjustably connected with the end 75 portions of the till, springs interposed between said rods and the till and arranged to transmit the upward thrust of said rods to the till, bolts carried by said rods and adjustable to vary the tension of said 80 springs, means for moving the chips upward in the chip holders to apply them to a card, and a platen movable into and out of position over said chip holders.

37. In a machine of the class described, 85 the combination with a suitable support, of a till mounted on said support to slide vertically, means carried by said till for holding a plurality of chip holders, cam actuated rods adjustably connected with the 90 end portions of the till, springs interposed between said rods and the till and arranged to transmit the upward thrust of said rods to the till, collars carried by said rods, bolts connected with said collars and adjustable 95 to regulate the tension of said springs, means for moving the chips upward in the chip holders to apply them to a card, and a platen movable into and out of position 100 over said chip holders.

38. The combination with a suitable support, a vertically movable chip holder having a pocket to hold a stack of chips, and means for moving said chip holder vertically, of a platen movable into position over 105 said chip holder, and card-holding fingers carried by said platen, said chip holder being movable between said fingers into engagement with the card.

39. The combination with a suitable support, a vertically movable chip holder, and means for moving said chip holder vertically, of a platen movable into position over 110 said chip holder, and card-holding fingers carried by said platen, the marginal portions of said chip holder being cut away to 115 permit the chip holder to move between said fingers into engagement with the card.

DAVID A. URIE.
